UNITED STATES PATENT OFFICE.

CHARLES F. HACKMAN, OF STAUNTON, ILLINOIS.

DESIGN FOR A CARPET-STRETCHER.

SPECIFICATION forming part of Design No. 20,850, dated June 23, 1891.

Application filed May 22, 1891. Serial No. 393,767. Term of patent 7 years.

To all whom it may concern:

Be it known that I, CHARLES F. HACKMAN, of the city of Staunton, Macoupin county, and State of Illinois, have invented a certain 5 new and original Design for Carpet-Stretchers, of which the following is a full, clear, and exact description, reference being had to the accompanying drawings, forming a part hereof.

In the drawings, Figure 1 is a perspective 10 view of a carpet-stretcher, showing my design; and Fig. 2 is a side view of same.

The leading feature of my design is a body 1, provided with rectangular ends 2 and 3 and having curved depressions 4 in the opposite 15 edges of the body intermediate of said ends. One face of the body 1 is in the form of a continuous curved line, as seen in Fig. 2, and the opposite face of said body is provided with a straight or plane surface 5, extending from 20 the outer terminal of end 2 inwardly to the curved depressions 4, and a curved depression 6, extending from the inner end of said plane surface to (or near to) the end 3 of the body. The end 3 of said body has a series of cylindrical projections 7, whose free ends are conical in contour, and projecting from the opposite end of the body is a pair of crescent-shaped figures 8. The plane surface 5 is provided with a series of circular depressions 9, and within the body 1 and located between 25 said plane surface and the terminal 3 a series of elongated curved depressions 10 is formed, and between these curved depressions and the edges of the body there is a series of diamond-shaped depressions 11, said diamond-shaped depressions being located in lines parallel with the curved lines of side depressions 4. On the edge of the body are also rounded projections 12.

What I claim is—

The design for a carpet-stretcher, as herein shown and described.

In testimony whereof I affix my signature in presence of two witnesses.

CHAS. F. HACKMAN.
